UNITED STATES PATENT OFFICE

2,146,726

PREFABRICATED BUILDING

Joseph C. Estes, Woonsocket, R. I., assignor to
Austin T. Levy, Harrisville, R. I.

Application September 22, 1937, Serial No. 165,107

12 Claims. (Cl. 72—18)

My invention relates to prefabricated buildings. It has heretofore been proposed to construct buildings having partition walls built up of paneled structures comprising an insulating board and plaster anchoring material adjacent each side of the board and spaced therefrom by means of reinforcing rods, and to rest the panels directly upon the sub-flooring and provide holes where necessary in the sub-flooring to receive the lower ends of the rods. Another method of supporting such a partition structure has been to support the panels and channel studs at their lower edges by a horizontal channel member which is adapted to rest directly on the sub-flooring, and to permit the anchoring material supporting rods to have their lower ends extend downwardly into the channel member. As a result of the first of these constructions, it has been necessary to make provision in the sub-flooring to receive the lower ends of the anchoring material supporting rods, and since these rods are spaced relatively closely together, the provision of holes to receive the rods and the fitting of the latter in these holes has required an appreciable amount of time and labor. The latter of these methods of supporting the partition structure has also necessitated the use of an additional and relatively expensive lower metal channel member for receiving the ends of both the panel and the anchoring material supporting rods, all in such manner as to result in a high cost of fabrication. Moreover, difficulty has been experienced with both these previous methods of erecting partition walls in applying the outer plaster coating since the latter extended to the sub-flooring, and in applying the same in a coating of equal thickness over its entire area, since no guiding means was provided to assist the plasterer.

My invention has among its objects to remedy the above difficulties and to decrease construction cost in erecting such partition walls, while facilitating and expediting assembly and producing an improved wall. A further object of my invention is to provide an improved construction, whereby it is made possible to eliminate the drilling or other hole forming operations necessary to supply openings to receive the rods of the wall structure and all need for inserting the rods in such holes, while also securely fastening the panels and eliminating all need for such bottom channel members as heretofore provided. A further object of my invention is to produce an improved partition structure, wherein, while obtaining these advantages, it is also made possible to obtain a greatly improved finished wall sur-

face through the provision of an improved bottom support and guide strip for the plaster. These and other objects and advantages of my improved partition structure will, however, hereinafter more fully appear.

In the accompanying drawing, I have shown for purposes of illustration one embodiment which my invention may assume in practice.

In the drawing,—

Figure 1 is a broken perspective view of a partition wall of my improved construction, the same being shown as first erected and when completed, and

Fig. 2 is a plan view of the improved partition supporting member.

Referring to Figure 1, it will be noted that a suitable sub-flooring 1 of heavy matched boards is provided as a continuous supporting structure resting on any usual floor joists (not shown). In my improved construction, upon this sub-flooring 1 and in any desired location, an improved partition supporting base, herein comprising a base member or strip 2, is nailed or secured by spikes or nails 3 and the partition is carried on and cooperates with this member 2 in an improved manner.

In accordance with my invention, the partition supporting member or strip 2 is of a thickness substantially equal to that of the hardwood, tongue and groove finish flooring 4 which is to be laid on the sub-flooring in the usual manner when the partition walls are completed. This supporting member 2 is also of such width that it will receive well within its lateral limits a panel board or insulating sheet 5 of the usual thickness, and reticulated metal 6, forming an anchoring material for the plaster and spaced from the panel board by supporting rods 7. Moreover, this member 2 is of such greater width than the panel as to extend on each side thereof substantially beyond the anchoring material 6 and provide a support 2a on each side of and below the panel to support a finish coating of plastering 8, so that the coat of plaster may be made substantially flush, when completed, with the outer edge of the supporting member 2. Further, it will be noted that the member 2 has vertical sides 2b extending below the bottom edge of both plaster surfaces for a substantial distance, herein equal to the thickness of the flooring 4, so that the plaster may be readily applied and finished off flush therewith, it being understood that the plaster is preferably applied before laying the floor 4.

In further accordance with my invention, I provide longitudinal grooves 9 in the upper sur-

face of the supporting member 2 to receive the lower ends of the anchoring material supporting rods 7. As illustrated on the broken section, the grooves 9 are disposed in spaced parallel relation so as to form a supporting area 10 of approximately the same width as the thickness of the wall panel 5, to support the panels along their bottom edges. Further, it will be noted that the grooves 9 are so disposed as to be close to the surface of the wall panels in such manner as to receive and support the lower ends of the rods 7, which, as usual, rest against the surface of the panel boards 5 and space therefrom the anchoring material 6. Also, the anchoring material is held against the rods in any usual manner, as by twisted wire 11 passing through apertures in the wall panels and extending over opposing rods 7 on each facing of the wall panel, and the bottom edge of this anchoring material extends into close proximity to the supporting surface 2a. Further, with the panel boards 5 assembled substantially as heretofore, and held in position by channel studs 12 arranged in back to back relation, the lower ends of these channel studs 12 are carried on a suitably connected foot plate 13, of the same width as the supporting member 2 and nailed by the spikes or nails 3, through convenient holes in the plate, to the supporting member 2 while also nailing the latter to the sub-floor 1.

As a result of my improvement, it will be noted that improved provision is made not only to support and locate the panel boards, channel studs, and anchoring material supporting rods, but also to facilitate and expedite partition assembly and to support the outer plastering and furnish a guide by which the plastering may be applied in an even coating to the outer surface of the partition wall. Note further that this results in a unitary wall of consistent thickness and standard appearance which is firmly secured to the flooring structure. Additional strength is given to the support of the partition wall by the finish flooring 4 which is laid after the coating of plaster has been applied to the wall, the boards in the finish flooring (herein at their ends) abutting against the sides of the supporting member 2 in such a way as further to increase the firmness of the support for the partition wall structure. Attention is here directed to the inexpensive manner of assembling the partition wall and to the low cost of the partition supporting member, which may be a wooden strip with the grooves milled on the surface thereof, all while obtaining an improved supporting and locating means for the partition wall.

While I have in this application specifically shown one of the embodiments which my invention may assume in practice, it will be understood that this form is shown for purposes of illustration and that the same may be modified and embodied in other forms without departing from its spirit or the scope of the appended claims.

65 What I claim as new and desire to secure by Letters Patent is:—

1. In a wall construction, a base strip having a panel supporting portion and recessed means therein, stud means supported on said supporting portion, a wall panel held between said stud means and disposed above said recessed means, and coating anchoring spacing means on said panel extending into said recessed means.
2. In a wall construction, a base having a supporting portion and a longitudinal groove, stud

means supported on said supporting portion, a wall portion held between said stud means and disposed above said groove, and coating anchoring spacing means on said panel extending into said longitudinal groove.

5 3. In a wall construction, a base member having a supporting portion and a longitudinal groove, stud means supported on said supporting portion of said member, a wall panel held between said stud means and disposed above said groove, said longitudinal groove extending substantially parallel with the lower edges of said panel, plaster anchoring material overlying said panel, and spacing means supporting said anchoring material and receivable at their lower ends in said groove.

10 4. In a wall construction, a base strip having a supporting portion, a recessed portion therein, and a coating support on the opposite side of said recessed portion from said supporting portion, stud means supported on said first portion, a wall panel held between said stud means and disposed above said recessed portion, anchoring means on said panel having spacing means in said recessed portion, and a coating overlying said anchoring means and supported on said coating support.

15 5. In a wall construction, a base comprising a base member having a longitudinal groove, stud means supported on said member, a wall panel held between said stud means and above said member, coating anchoring means on said panel having spacing means in said groove, and a coating support on said base member extending along said groove on the outer edge of said member.

20 6. In a wall construction, a base comprising a base member having a longitudinal groove, stud means supported on said member, a wall panel held between said stud means and above said member, coating anchoring means on said panel having spacing means in said groove, a coating support on said base member extending along said groove on the outer edge of said member, sub-flooring below said base member, and finish flooring laid on said sub-flooring and engaging 25 the side of said coating support.

25 7. In a wall construction, a base member having a supporting portion and parallel longitudinal grooves, upright stud means supported on the supporting portion of said member, a wall panel held between said stud means and disposed above said grooves, plaster anchoring means disposed over said wall panel, and means spacing said anchoring means from said panel and having the lower ends thereof received in said grooves.

30 8. In a wall construction, a base comprising a member having a supporting portion, recessed portions on opposite sides thereof, and laterally extending plaster supports outside said recessed portions, stud means supported on said supporting portion, a wall panel held between said stud means and disposed above said recessed portions, plaster anchoring means overlying the opposite faces of said panel having spacing means extending into said recessed portions, and plaster applied over said anchoring means supported on said plaster supports and extending to the outer edges thereof.

35 9. In a wall construction, a base comprising a member having parallel longitudinal grooves and laterally extending plaster supports outside said grooves, upright stud means supported on said member, a wall panel held between said stud means and resting on said member between the grooves, plaster anchoring means disposed over 40 75

said wall panel, means including rods spacing said anchoring means from said panel and received at their lower ends in said grooves, and plaster applied over said anchoring means and extending to the edge of said base member and supported on said supports.

10. The combination in a wall structure, of sub-flooring, a partition supporting member resting on said sub-flooring and having parallel longitudinal grooves and plaster supports extending laterally outside said grooves, channel studs supported on said member, a wall panel held between said channel studs, reticulated metal disposed over said wall panel, means including rods 15 spacing said reticulated metal from said wall panel and having lower ends received in said grooves, plastering extending to the edge of said first mentioned member and supported on said supports, and flooring abutting against the longitudinal edges of said first mentioned member 20 beneath said supports.

11. In combination, a prefabricated wall structure having panels carrying means for spacing reticulated coating carrying metal from the surface of the panels, and a base strip comprising a member disposable longitudinally of said panels for supporting the latter and having parallel recessed means for receiving said spacing means and also having coating supporting surfaces on opposite sides of said member outside said recessed means. 5

12. In combination, a prefabricated wall structure having panels carrying means for spacing reticulated coating carrying metal from the surface of the panels, and a base member comprising a member disposable longitudinally of said panels for supporting the latter and having parallel grooves for receiving said spacing means and also having coating supporting surfaces on opposite sides of said member outside said grooves. 10 15

CERTIFICATE OF CORRECTION.

Patent No. 2,146,726.

February 14, 1939.

JOSEPH C. ESTES.

It is hereby certified that error appears in the printed specification of the above numbered patent requiring correction as follows: Page 2, second column, line 2, claim 2, for the word "portion" read panel; and that the said Letters Patent should be read with this correction therein that the same may conform to the record of the case in the Patent Office.

Signed and sealed this 25th day of April, A.D. 1939.

Acting Commissioner of Patents.

said wall panel, means including rods spacing said anchoring means from said panel and received at their lower ends in said grooves, and plaster applied over said anchoring means and extending to the edge of said base member and supported on said supports.

10. The combination in a wall structure, of sub-flooring, a partition supporting member resting on said sub-flooring and having parallel longitudinal grooves and plaster supports extending laterally outside said grooves, channel studs supported on said member, a wall panel held between said channel studs, reticulated metal disposed over said wall panel, means including rods 15 spacing said reticulated metal from said wall panel and having lower ends received in said grooves, plastering extending to the edge of said first mentioned member and supported on said supports, and flooring abutting against the longitudinal edges of said first mentioned member 20 beneath said supports.

11. In combination, a prefabricated wall structure having panels carrying means for spacing reticulated coating carrying metal from the surface of the panels, and a base strip comprising a member disposable longitudinally of said panels for supporting the latter and having parallel recessed means for receiving said spacing means and also having coating supporting surfaces on opposite sides of said member outside said recessed means. 5

12. In combination, a prefabricated wall structure having panels carrying means for spacing reticulated coating carrying metal from the surface of the panels, and a base member comprising a member disposable longitudinally of said panels for supporting the latter and having parallel grooves for receiving said spacing means and also having coating supporting surfaces on opposite sides of said member outside said grooves. 10 15
